UNITED STATES PATENT OFFICE.

JOHN C. PARK, OF BUFFALO, NEW YORK.

IMPROVEMENT IN WELDING AND REPAIRING RAILROAD-BARS.

Specification forming part of Letters Patent No. 37,972, dated March 24, 1863.

To all whom it may concern:

Be it known that I, JOHN C. PARK, of Buffalo, in the county of Erie and State of New York, have invented a new and Improved Machine for Welding Together and Repairing Railway-Bars; and I do hereby declare that the following is a full, clear, and exact description of the same, reference being had to the accompanying drawings, forming part of this specification, in which—

Figure 1 is a top view of the machine. Fig. 2 is a longitudinal vertical section of the same. Fig. 3 is a front end view of the same.

Similar letters of reference indicate corresponding parts in the several figures.

This machine is composed of a ram and a die, having their faces of the form of the two sides of a railway bar, the die secured firmly to a fixed block or bed-plate, and the ram being fitted to guides on the said block or plate and attached to a piston working within a steam-cylinder secured to the said block or plate, the object being the direct application of steam-power to the welding and repairing of railway-bars.

To enable others skilled in the art to make and use my invention, I will proceed to describe its construction and operation.

A is the block or bed-plate, to which all the parts of the machine are attached, made of cast-iron of sufficient weight to give it great solidity.

B is the die, having its face of the form of one side of a railway-bar, D, and bolted firmly on the top of the block A.

C is the ram, having its face of the form of one side of the bar D. This ram is fitted to slide toward and from the die B in horizontal guides d d, bolted to the block A, and it is keyed securely to one end of the rod E of the piston F, which works in the short horizontal steam-cylinder L. This cylinder may be cast with or otherwise firmly secured to the block A, and the rod of the piston works through stuffing-boxes in both ends of it.

To the outer end of the steam-cylinder—that is to say, the end farthest from the ram C—there is attached a valve chest, G, which is fitted with a valve of any suitable kind, by which steam may be admitted from the said chest into the cylinder, to force the piston and ram toward the die B, and afterward allowed to exhaust for the purpose of permitting the piston to come back again, the said valve being worked by means of a hand lever, H.

I is the pipe, by which steam is admitted from a boiler to the valve-chest G.

J is the exhaust-pipe.

K is a branch-pipe leading from the pipe I to the inner end of the cylinder—that is to say, the end nearest the ram—and fitted with a stop-valve, a, which is kept closed by a loaded lever, b, but opened by the pressure of steam when the said lever is raised for the purpose of admitting steam to the inner end of the cylinder, to force the piston back, after the communication between the outer end of the cylinder and the exhaust-pipe has been opened by the main valve in the chest G. There is a swage, M, formed upon or secured to the block A, for the reception of one side of the railway-bar, and the upper part of the die B is so formed (see Fig. 2) as to constitute a swage for the other side of the bar.

The operation of welding together two railway-bars or portions thereof in this machine is as follows: The two bars or portions thereof having had their ends properly heated, the ram C is drawn back from the die B by the admission of steam through the pipe K to the inner end of the cylinder, and the bars or portions thereof are laid end to end upon the block A, between the die B and ram C, and after the two heated ends have been closed by striking the opposite ends with sledge-hammers, the main valve is opened by the lever H, to admit steam to the outer end of the cylinder, and, as the valve a has been previously closed, the steam forces the piston toward the inner end of the cylinder, and causes the ram C to force the rail against the die B, and so perform the welding process. This operation of the piston and ram may be repeated one or more times, if necessary, and when the sides of the joint have been brought to the desired shape by these means, the ram holds the joint immovably while the weld is finished on the face of the rail by the use of hand-hammers.

What I claim as my invention, and desire to secure by Letters Patent, is—

The machine for welding or repairing railway-bars, composed principally of a block or bed-plate, A, a die, B, a ram, C, a piston, F, and a steam-cylinder, L, the whole combined to operate substantially as herein set forth.

J. C. PARK.
